(57) **CLAIM**

The ornamental design for a hammer nut, as shown and described.

DESCRIPTION

FIG. 1 is a front, top, right perspective view of a hammer nut showing the new design;

FIG. 2 is a rear, top, left perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a cross-sectional view thereof as indicated in FIG. 6; and,

FIG. 8 is an enlarged cross-sectional view thereof as indicated in FIG. 7.

The broken lines of uneven length shown in the drawings illustrate the boundary of the claimed design and form no part thereof. The broken lines of longer length shown in the drawings illustrate portions of the hammer nut that form no part of the claimed design. The broken lines of shorter even length shown in the drawing illustrate the cross-sectional or enlarge views.
